UNITED STATES PATENT OFFICE.

EDWARD W. BUEHL, OF CHICAGO, ILLINOIS.

DESIGN FOR A PIE-FORK.

SPECIFICATION forming part of Design No. 22,992, dated December 26, 1893.

Application filed March 20, 1893. Serial No. 466,944. Term of patent 7 years.

To all whom it may concern:

Be it known that I, EDWARD W. BUEHL, a citizen of the United States of America, residing at Chicago, in the county of Cook and State of Illinois, have invented a new and original Design for a Pie-Fork, of which the following is a specification.

My design is illustrated in the accompanying drawings by means of two figures, of which—

Figure 1 is a view of the flat side of the fork; and Fig. 2 is an edge view looking from left to right in Fig. 1.

In the drawings, the handle is lettered A, and the tines B. The front of the fork is shown in Fig. 1, and the portion between the

handle and the tines C, is rearwardly convex as is common in forks, but has upon the left hand side a lateral extension, c, much thinner at the edge than elsewhere and convex in a lateral direction as shown in the figures. This lateral projection, it should be noticed, stops some distance from the ends of the tines.

I claim as new and desire to secure by Letters Patent—

The design for a pie fork herein shown and described.

EDWARD W. BUEHL.
